DIRECTING APPARATUS

Joseph Raymond Jasse, Paris, France, assignor to Societe Nouvelle des Etablissements Brandt, Paris, France, a French body corporate

Application May 12, 1953, Serial No. 354,454

Claims priority, application France May 14, 1952

1 Claim. (Cl. 89—41)

The present invention relates to the directing of artillery equipment adapted for launching selfpropelled projectiles.

The effect of the wind on these selfpropelled projectiles has not heretofore been suitably corrected owing to a lack of equipment sufficiently accurate and instantaneous to permit of a continuous correction. It is well known that the detrimental effect of the wind on the performance of suchlike projectiles is particularly marked during the selfpropelled period of flight which is of very short duration. The correction introduced must therefore be that which exactly corresponds to the wind acting in the vicinity of the firing piece at the moment of issue of the projectile. It is also known that the action of the wind on selfpropelled projectiles differs according as those projectiles are stabilized by vanes or by gyroscopic means. In the case of vaned projectiles, the component of the wind in the plane of fire acts upon the range and must be compensated for by a modification of the angle of elevation, whereas the transverse component of the wind, since it causes a deviation from the plane of fire, requires a correction in azimuth. In the case of gyroscopically stabilized projectiles, as a rule the reverse is true. The component of the wind perpendicular to the plane of fire causes a rise or fall in the trajectory which must be corrected for by a modification in the angle of elevation whereas the longitudinal component, although unaffected point blank firing along the horizontal, acts upon the direction of the projectile in a manner depending on the slope of the trajectory, which implies a direction correction dependent on this slope. With some gyroscopically stabilized projectiles, it might occur that the two components of the wind act simultaneously upon the direction and range.

In any case, to compensate the effect of wind on selfpropelled projectiles, it is necessary to modify in a continuous and automatic way the lay of the launching apparatus in elevation and azimuth.

The invention has for its object to provide an improved directing or pointing apparatus for artillery material adapted for launching selfpropelled projectiles, this apparatus permitting corrections for wind in direction and range to be made automatically, instantaneously, and continuously.

The invention has more particularly for its object to provide a directing apparatus wherein the directing device includes a sighting device responsive to an anemometric device placed in the immediate vicinity of the latter and adapted for modifying the position of this sighting device in a manner depending on the speed and direction of the wind.

Other features and advantages will be apparent from the ensuing description. In the accompanying drawings given solely by way of example:

Fig. 1 is a diagrammatic elevational view of a self-supporting firing piece equipped with a directing or pointing apparatus improved in accordance with the invention,

2

Fig. 2 is a rear view in elevation of the directing device or "directing apparatus proper."

Fig. 3 is a front view thereof including the sight,

Figs. 4 and 5 are transverse and longitudinal sections thereof,

Fig. 6 is a diagram of the various electrical connections between the anemometric head and two motors of the directing device, and

Figs. 7 and 8 are views in elevation with cut-away portions of two modifications of the directing device.

In the embodiment shown in Figs. 1 to 6, the invention is applied to a launching piece for several selfpropelled projectiles. This piece comprises a motor vehicle 1 provided with several similar launching tubes 2, the directing being obtained by means of a directing device or "directing apparatus proper" A, provided with a sighting device constituted by a sight or telescope 3. This directing device is connected by means of a servomechanism B to an anemometric head C adapted for correcting the directing data as a function of longitudinal and transverse components of the wind in the vicinity of the launching piece, the electric current necessary for the connections between the directing device A and the anemometric head C being supplied by an electric source 20 consisting of a battery D having a voltage across the end terminals a and b of the order of 24 volts, an intermediate terminal being provided at o (see Fig. 6). A cable 4 connects the anemometric head C to the servomechanism B, which is connected by a cable 5 to the source D, and by another cable 6 to the directing device A.

These various devices will now be described in turn.

(a) *Directing device A (Figs. 2 to 5).*—It comprises a metal block or support 7 provided with a slide 8 having a dovetailed section adapted for engaging in a slide-way carried at the side of the firing tube carriage, a lock 8^a (Fig. 2) which ensures the locking into position of the slide 8 when a lever 8^b is tipped about an axis 8^c. In a bore having a vertical axis XX provided in the support 7, is journaled a cylindrical nut 9 held axially,

40 through the medium of a shoulder 10, by a ring 11 fixed to the support 7 by screws 12 (Fig. 5). In the tapped hole in the nut 9 is screwed a screw 13 the head of which includes a recess 14 in which is housed a ball 15. The nut 9 may be driven in rotation directly by hand through 45 the medium of a raising knob 16 integral with a worm 17 which is journaled in two rings rigidly secured in the support 7 and which is in mesh with a toothed portion provided on the outer face of the nut 9. By rotating the knob 16, the screw 13 can be displaced axially.

50 This screw is prevented from turning in a manner hereinafter described. This displacement of the screw 16 introduces a correction in elevation according to the distance of the objective. The positions of the nut 9 about the axis XX may be read off a first graduated drum 19 which is integral with this nut and moves before an index 20 (Fig. 2) provided on a plate 21 fixed to the support 7.

In order to introduce corrections in elevation compensating the effect of the wind (range), the screw 13 may be driven in rotation about the axis XX by means of an electric motor 23 housed in a housing 24, which posts

60 25 connect to the support 7. This motor, which is reversible and the feed of which is dependent on the anemometric head 9 as will be hereinafter explained drives, through the medium of its shaft 26 and a step-down gear including a gear pinion 27, a gear wheel 28, a worm 29,

and a worm wheel 30, a shaft 31 disposed in the extension of the screw 13. On this shaft is pinned a member 32 supporting two diametrically opposed rods 33 which slide in a crosspiece 34 fixed on the end of the screw

70 31. According to the direction of rotation of the motor 23, the screw 13 screws or unscrews itself with respect to the nut 9 and causes the ball 15 to be displaced along

the axis XX. The rotation of the screw 13 can be read off a second graduated drum 35 in front of a second index 36 provided on a plate 37 also fixed to the support 7.

The ball 15 abuts against a heel 38 fixed on the end of a cradle 39 mounted to pivot about an axis 40 in a fork 41 integral with a turret 42 rotatively mounted on the support 7 through the medium of a journal 43 having an axis VV parallel to axis UU. The axis WW, about which the cradle 39 pivots on the turret 42, is normal to the axes UU and VV and is, therefore, horizontal. Correction for deviation in direction is obtained by rotating the turret 42 about the axis VV. The cradle 39 is biased against the ball 15 by means of springs 43^a and includes a dovetailed slideway 44 in which is engaged the sight or telescope 3 (see Fig. 3). The sight 3 is held in position by a lock 45 protruding from the bottom of the slideway and biased by a spring 46. This lock is pivoted at 45^a on the cradle and includes a tail 47 upon which it suffices to press when it is desired to free the sight 3. The rotation of the turret 42 about the axis VV is ensured by means of a second reversible motor 48 housed in an auxiliary housing 49 attached to the side of the support 7 and the housing 24. The shaft 50 of this motor is connected by means of a step-down gear train 51 to a toothed sector 52 provided at the periphery of the turret 42.

The directing or pointing device A is completed by an auxiliary device by means of which corrections in angle of elevation are possible by hand setting of the screw 13 in the event, for example, of a break-down in the operation of the anemometric device C or the servomechanism B caused by, for example, a run-down battery D. This device, shown in Fig. 4, comprises a screwed piece 53 provided with a foot 54 attached to the housing 24 in such manner that the axis of the screwed part 53 coincides with the axis of the gear wheel 28 forming part of the transmission between the motor 23 and the screw 13. On the screwed part 53 is screwed a nut 55 which may be turned with the aid of a radial pushbar 56. This nut is ordinarily held in position by means of a lock 57 which is movable in a radial slot 58 provided in the nut and which is biased by a spring 59 into one or other of two grooves 60 provided in the screwed part 53 in two perpendicular planes through the axis of the latter. The side walls of the groove 60 are beveled so that when the pushbar 56 is urged in rotation about this axis in one direction or the other, the lock 57 automatically disengages from the groove in opposition to the action of the spring 59. Against the outer face 61 of the nut 55 abuts a control knob 62 keyed on a shaft 63 rotatively and slidably mounted in the nut 55. This shaft comprises inside the housing 24 a flange 64 provided with two diametrically opposed pins 65 capable of engaging respectively in one or other of two diametrically opposed openings 66 in the gear wheel 28. A spring 67 abuts against a shoulder 68 provided in the screwed part 53 and against the flange 64 and urges the shaft 63 towards the right in the view shown in Fig. 4, so that the pins 65 engage the openings 66. In the disengaged position, the various members are in their positions shown in Fig. 4. The nut 55 is sufficiently unscrewed that its face 61, in urging the control knob 63 towards the left, holds the pins 65 out of engagement with the openings 66.

When it is desired to engage the auxiliary device, the nut 53 is rotated by means of the pushbar 56, so as to screw it in a direction to displace its face 61 towards the right in the view shown in Fig. 4. The control knob 62 and the shaft 63 are temporarily retained by the abutment of the pins 65 against the face of the gear wheel 29. When the nut 53 has been stopped by the lock 57 in a desired engaged position, it suffices to turn the control knob 62 in any direction until the pins 65 come into line with the opening 66, in which they engage under

the action of the springs 67, whereupon, in turning the control knob 62 in one direction or the other, the screw 13 may be rotated by hand and thereby effect any desired correction in the angle of elevation. This correction may be read off the graduated drum 35 opposite the index 36.

Fig. 6 will now be considered, which represents, by way of example, an embodiment of the anemometric head C and the mechanism B connecting this head to the directing device A. This anemometric head and this mechanism will be described in turn.

Anemometric head C.—It comprises a hollow support 70, in which is rotatively mounted, about an axis XX, a shaft 71 which is driven in rotation, through the medium of a speed reducer 72, by a reversible electric motor 73. On the upper end of the shaft 72, above the support 70, is fixed a plate 74 (Fig. 1) forming the lower part of a protective cage having a side wall 75 which is perforated in order to allow the free passage of the wind therethrough. Inside the cage is disposed a cylindrical casing 76 which has an axis YY perpendicular to the axis XX and is fixed to the plate 14 so that it and its conjugate parts may take part in the rotation of the shaft 71. Inside the cylindrical casing 76 is disposed a wind wheel or rotor 77 which is keyed on a shaft 78 having an axis YY and journalled in bearings supported by the casing 76. From this cylindrical casing is suspended, about pivots 79, a vane or flap 80. The axis ZZ of these pivots is disposed parallel to the axes YY and XX. On either side of the mean position occupied by this vane 80 under the effect of the force of gravity or a return spring (in the case of an astatic vane), the plate 74 carries two contact studs 81 and 81^a insulated from this plate and with either one of which this vane enters into contact as soon as the direction of the wind veers towards to the right or left of the vertical plane through the axis YY. Conductors 82 and 82^a lead from these contact studs to contact or slip rings 83 and 83^a fixed on the shaft 71 and on which rub two brushes 84 and 84^a which conductors 85 and 85^a connect to one of the ends of one or other of two relay coils 86 or 86^a. The two other ends of these coils are connected by a single conductor 87 to the terminal b of a source of electricity D, so that one or other of these relays is energized according as the wind causes the vane 80, which is earthed, to contact the contact stud 81 or 81^a. The two relays control two reversing switches 88 and 88^a arranged as polarity reversers and connected to earth at 89, to the terminals of the motor 73 by conductors 90 and 91, and to an intermediate terminal c of the source D by another conductor 92.

As soon as the wind veers to one side or the other of the vertical plane through the axis YY, the vane oscillates and, in contacting one of the studs 81 and 81^a, causes one of the relays to be energized. This relay closes one of the reversing switches which in turn results in a voltage being applied across the terminals of the motor 73 in one direction or the other. This motor drives in rotation the movable unit about the axis XX in a direction to return the plane containing the axes YY and ZZ to a position in which it is parallel with the direction of the wind. This permits an automatic, accurate, and step by step, orientation of the wind wheel so that the axis of the latter always lies parallel to the wind direction. Thus, the rotation of the wind wheel is an exact function of the wind component parallel to the axis of the wind wheel, i. e. the horizontal wind component of this axis is horizontal.

For determining or detecting the velocity of the wind along this component, the wind wheel 77 and its shaft 78 are combined with a current modulating device. This device comprises a small conductive star 93 provided with an odd number of equispaced, radial branches or arms. This star is fixed on the shaft 78 through the

medium of a device constituting a capacitor, which is diagrammatically represented at C₅. One of the electrodes of this capacitor is connected to the star and the other is earthed through the shaft 78. The star 93 cooperates with two conductive points 94 and 95 fixed, through the medium of insulators, to the cylindrical casing, and disposed symmetrically about the axis YY so that their ends are in the immediate vicinity of the transverse plane containing the branches of the star. Hence, when the branches pass by the point 94, the point 95 is mid-way between two other branches and vice-versa. The point 94 is at a high potential, for example, of the order of 4000 volts. It is connected by a conductor 96 to a ring 97 fixed on the shaft 71 and on which rubs a brush 96 which a conductor 99 connects to a rectifying and transforming device including a step-up transformer 100 the primary 101 of which is connected by conductors 102 to a feed device, whereas the secondaries 103 and 104, feed a rectifying valve 105. The other point 95 is connected by a conductor 106 to a ring 107 fixed on the shaft 71 and on which rubs a brush 108 which a conductor 109 connects to the device D.

The anemometric head is completed by two sets of cams 110, 111, and 110^a, 111^a, fixed on the shaft 71. Each of the cams 110 and 110^a includes two semi-circular portions having different radii and connected together by two diametrically opposed steps. They cooperate with followers 112 and 112^a which carry the movable contact studs of switches 113 and 113^a, the movable studs being connected by conductors 114 and 114^a to the device B, whereas the fixed contact studs are earthed. The follower 112 and the cam 110 are so arranged on the shaft about the axis XX that the diametral line through the steps of the cam passes the follower when the direction of the wind in plan coincides with the plane of fire P. The cam 110^a is disposed about the axis XX with a phase lag of 90° relative to the cam 110. The cams 111 and 111^a are respectively cosine and sine cams if the directing apparatus is for firing vanned projectiles and sine and cosine cams if gyroscopically stabilized projectiles are being fired. Against each of these cams is resiliently urged a follower, 115 or 115^a, carrying the slider, 116 or 116^a, of a potentiometer 117 or 117^a. The slider, 116 or 116^a, is insulated from earth and is connected by a conductor, 118 or 118^a, to the device B, and the resistor, 117 or 117^a, has one of its ends earthed and the other end is connected by a conductor, 119 or 119^a, to the device B. These cams are so arranged as to change the respective positions of the sliders 116 and 116^a on the resistors 117 and 117^a proportionally to the trigonometrical cosine and sine functions (or conversely) of the angle between the plane of fire P and the direction in plan of the wind.

Unit B.—This unit, housed in a case, comprises a high tension feed device E, a frequency meter F and two follow-up, calculating, transmitting, and exploiting devices G and G^a, pertaining to the motor 23 and the motor 48 respectively.

Feed device E.—It comprises a converter composed of a motor 120, connected to the terminals b and c of the source D, and an alternating current generator 121, the rotor of which is coupled to the shaft of the motor 120. To the terminals of this generator 121 are connected the feed conductors 102 of the rectifier 100—105, and the primary of a transformer 122, the secondary of which feeds two rectifying valves 123 and 124 adapted to give, in combination with normal filters 125 and 126, at the terminal d a high voltage +HT (relative to the earth of zero voltage) equal, for example, to +150 volts, and at the terminal e a voltage —HT equal, for example, to —100 volts.

Frequency meter F.—The conductor 109, which is connected to the point 95 in the anemometric head C, is

connected to earth through a capacitor C₁ and a resistor R₁ and is also connected, by a capacitor C₂, to the two grids of a thyratron V₁ tetrode (for example of the type 2D21). These two grids are also connected to the cathode of the thyratron by a resistor R₂, and to the —HT by a resistor R₃. The cathode of the thyratron is connected to earth through potentiometers 117 and 117^a and through a capacitor C₄. The anode of the thyratron is connected to the HT (+150 volts) by two resistors R₄ and R₅, connected in series. A capacitor C₃ connects the common connection of these two resistors to the cathode.

Follow-up device G.—The slider 116 of the potentiometer 117 is connected to the grid of the triode V₂, which constitutes with the triode V₃ a double triode (for example of the type 12AU7). The two cathodes of this double triode are connected together and to the —HT by a resistor R₆. The anodes of these triodes are connected to the two coils 127 and 128 of a polarized relay r₁, the ends of these coils not connected to the anodes of the double triode being connected together and to the high tension +HT, the manner of connecting being such that the fields produced in the two coils of the relays by the anode currents from the two triodes V₂ and V₃ are in opposition. The contact 129 of this polarized relay r₁ connects the +12 volts to the coil 130 of a relay r₂ having two reversing switches 131 and 132, which are so connected as to reverse the polarity. Thus the +12 volts and earth are respectively connected to the two contact blades of this relay in one direction when it is not energized, and in the opposite direction when it is energized. The two blades of this relay are connected to a third coil 133 of the relay r₁ in series with a resistor R₇. These two blades are also connected to the two blades 134 and 135 of a relay r₃ energized, with another relay r₄, by the +12 volts across the contact 113, which is controlled by the cam 110 integral with the shaft 71 and is opened when the wind comes from the right relative to the plane of fire P. The relay r₃ is also connected for reversing the polarity, and at its output end is connected to the two poles of the motor 23, which controls the rotation of the screw 13, the position of which changes with the wind speed and direction. The relay r₄ is also a polarity reverser and, depending on whether it is energized or not, the direction in which the +12 volts and the negative voltage —HT (through the resistor R₈) are applied to the two ends of a potentiometer 136 is direct or permuted. The slider 137 of this potentiometer is controlled by the motor 23, so that its movement is related to that of the screw 13; it is, furthermore, connected to the grid of the triode V₃.

The device G^a, pertaining to the motor 48, is identical to the device G, except that the contactor 113 and the potentiometer 117 are replaced by the contactor 113^a and the potentiometer 117^a respectively.

The operation of the assembly of the directing or pointing apparatus is as follows. When a branch of the star 93, which is driven in rotation by the shaft 78 of the wind wheel 77, passes sufficiently near the fixed point 94 at the potential of 4000 volts, a spark or a series of sparks occur which charge the capacitor C₅. When, the wind wheel continuing its rotation, a branch of the star passes near the fixed point 95, a spark occurs and discharges the capacitor C₅ into the capacitor C₁ which in turn gradually discharges into the resistor R₁. Hence, there appears across the terminals of the capacitor C₁ well defined pulses that correspond to the passages of the branches of the star in front of the point 95. The capacitor C₂ transmits these pulses to the grids of the thyratron V₁. Normally, this thyratron is polarized by the voltage divider constituted by the two resistors R₂ and R₃, so that the polarization of the thyratron remains more or less constant when the potential of the cathode of this thyratron changes. At the moment when the grids of this thyratron receive a pulse, the latter ionizes, and the

capacitor C_3 , charged at the normal rate by the high tension through the resistor R_5 , discharges through the resistor R_4 (which constitutes a protective resistor limiting the current in the thyratron to a safe value) and across the thyratron itself.

After each discharge, the capacitor C_3 is recharged by the $+HT$ through the resistor R_3 . The recharging current, if it is to return to earth, must pass through the potentiometer 117; now since, as a first approximation, the quantity of electricity which charges the capacitor C_3 is always the same, the mean current in this potentiometer is proportional to the number of discharges per second, i. e. the rotative speed of the wind wheel 77. The mean voltage at the terminals of the potentiometer 117 is, then, proportional to this speed. The capacitor C_4 , which is in parallel with this potentiometer, allows through practically all of the alternating component of the recharging current of the capacitor C_3 . Thus at the terminals of this capacitor C_4 and across the potentiometer 117 there is a voltage which is proportional to the wind velocity and is substantially continuous. As the slider 116 of the potentiometer is controlled by the cosine cam 111 in the case of vaned projectiles, or the sine cam in the case of gyroscopically stabilized projectiles, there is in the conductor 118 a voltage which is proportional to the wind velocity component in the plane of fire, or in the plane perpendicular to the latter, i. e. the component which has to be taken into account for correcting the angle of elevation if the axes XX is vertical.

The operation and function of the servomechanism G will now be considered, it being supposed that the wind is coming from the right relative to the plane of fire P, so that the relays r_3 and r_4 are not energized. Since the double triode (V_2, V_3) has its two cathodes connected together and to the $+HT$ by the resistor R_6 , the sum of the currents of the two triodes is, as a first approximation, constant, the distribution of the currents of the two triodes only depending on the difference between the voltages of the two grids. The coils 127 and 128 of the relay r_1 are in opposition, so that this relay is or is not energized according as the voltage of the grid V_3 is greater or less than that of the grid of V_2 . If the relay r_1 is energized, the relay r_2 is energized, and vice-versa, and the voltage across the terminals of the motor 23 is in one direction or the other. This motor 23 controls the slider 137 of the potentiometer 136. The direction of the connections being correct, the motor moves the slider of this potentiometer into such position that the potential of this slider is equal (at least within a small tolerance) to that of the grid of the valve V_2 ; if the potentiometer is linearly wound, the distance between the position the slider assumes and the mid-way position is proportional to the component of the wind in the direction of the plane of fire, or in the direction perpendicular thereto according as the cam 111 is a cosine or a sine cam. However, the operation is a little more complex; the relay r_2 reacts on the relay r_1 through the medium of its coil 133 and through the resistor R_7 . The purpose of this reaction is to prevent the motor 23 from making the slider 137 of the potentiometer 136 oscillate about its position of equilibrium. Hence, when this slider arrives fairly near its position of equilibrium, the relays r_1 and r_2 oscillate at a relatively high frequency and the motor 23 is fed only with a slight vibration of insignificant amplitude.

If the wind veers to the left, the contact 113 closes, the relays r_3 and r_4 are energized, and the lower part of the potentiometer 136 is then connected to the $+12$ volts and, the connections of the motor 23 having been reversed so that follow-up still occurs, the slider 137 is brought by this motor 23 to a point in the lower part of the potentiometer which corresponds to a rotation of the shaft of this potentiometer in a direction opposite to that of the rotation which occurred when the wind came from the right.

The operation of the device G^a , which pertains to the motor 48 adapted for adjusting in direction, is identical.

In Fig. 7 there is represented a modification of the invention, in which the correction in direction (if the axis UU is vertical) or in elevation (if the axis UU is horizontal) is obtained by turning the sighting device unit about the axis UU. To this end, the turret 42 of the first embodiment is eliminated and the fork 41 on which is pivoted the cradle 39 is integral with the support 7^a. The unit comprising this support 7^a and the housing 24 is fixed on a plate 13^b adapted to be driven in rotation through a speed reducer 139 by the motor 48 housed inside a fixed housing 140.

In the special case of point blank range, only the transverse component of the wind is considered. This component necessitates a correction in direction in the case of vaned projectiles and in elevation in the case of gyroscopically stabilized projectiles. The apparatus is in consequence very simple, since it requires only one motor.

This type of apparatus is especially advantageous for anti-tank artillery in which the instantaneous, automatic, and continuous correction for wind is indispensable. For point blank range the simplified device shown in Fig. 7 may be utilized. In this device the cradle 39 is pivoted directly on the support 7^a under the control of the motor

23. The pivot axis of the cradle would be vertical if a vaned projectile is used, and horizontal if the projectile used is gyroscopically stabilized; the single cam 111 would then be a cosine cam.

In the foregoing description it had been supposed that the potentiometers were arranged for giving the screw 13 and the turret 42 displacements which were proportional to the wind components. However, there might arise instances where the required corrections were not proportional to these wind components. In this event the necessary modification could be effected by introducing between the cradle 39 or the turret 42 and the transmission means (screw 13 or the step-down gear 51) a correcting cam similar to that illustrated at 38 (Fig. 5) between the cradle and the ball 15. Alternatively, the potentiometers may be arranged in such manner as to give the true corrections directly.

The invention is not limited to the details of construction herein described and illustrated in the accompanying drawings which have been given merely by way of example.

The setting in elevation, which in the represented embodiment is obtained by hand by means of the control knob 16, may be obtained by acting on the nut 9 in any other manner, for example in a continuous manner if the target is moving.

The anemometer and its current modulating device may be of a type other than that described, provided it is possible to obtain the components of the wind in two directions perpendicular to one another in the form of rotations of shafts proportional to these components or to corresponding corrections for wind; for it is these rotations which, being automatically incorporated in the directing apparatus, modify the angular position of the sight or telescope by the necessary correcting angle.

The frequency meter F may be different from the thyratron type.

Each follow-up device or servomechanism G or G^a may include a pre-amplifying stage between the sliders of the potentiometers and the grids of the triodes V_2 and V_3 , this stage being incorporated in a similar way to the control stage of the relay r_1 as a symmetrical amplifier of the Loftin-White type.

The single capacitor C_3 may be replaced by a set of commutable capacitors which permits of an adjustment by steps of the sensitivity of the unit.

Instead of the potentiometers 117 and 117^a, controlled by the sine and cosine cams or conversely, any other device may be used, with which it would be possible to introduce between the voltage and the frequency any

other coefficient of proportionality, which may be constant or variable, a function of any parameter other than the angle between the direction of the wind and the plane of fire P, for example a correction related to the elevation brought about by means of the control knob 16, or even a coefficient that varies according to any law.

Without departing from the scope of the invention, the electrical devices connecting the directing apparatus with the anemometer may be replaced by any other means, which may or may not be electrical, such as, for example, flexible couplings whereby the same result may be obtained.

Having now described my invention what I claim as new and desire to secure by Letters Patent is:

In a directing device for launching pieces, adapted to launch selfpropelled projectiles, this launching piece including a carriage and an anemometric device, in combination: a support adapted for being fixed on said carriage, a turret mounted on said support to rotate about a first axis, a cradle mounted on said turret to pivot about a second axis perpendicular to said first axis, a nut journalled in said support, an auxiliary manually operable member, means for connecting said member to said nut for turning it in said support so as to bring about a setting in elevation or direction depending on the direction

of the pivotal axis of said cradle, a screw screwed into said nut, said cradle bearing on one of the ends of said screw, two reversible electric motors mounted on said support to drive said screw and said turret and connections which are electromagnetic, electromechanical, and electronic, for connecting said motors to said anemometric device so that said device receives corrections in elevation and direction one of which is dependent on the component of the wind in the plane of fire and the other is dependent on the transverse component of the wind.
